UNITED STATES PATENT OFFICE.

MICHAEL W. SHILLINGER, OF GRAND RAPIDS, MICHIGAN.

DESIGN FOR A LAMP SUPPORT.

Application filed March 28, 1928. Serial No. 26,046. Term of patent $3\frac{1}{2}$ years.

To all whom it may concern:

Be it known that I, MICHAEL W. SHILLINGER, a citizen of the United States, residing at Cody Hotel, Grand Rapids, in the county of Kent and State of Michigan, have invented a new, original, and ornamental Design for Lamp Supports, of which the following is a specification, reference being had to the accompanying drawing, forming a part thereof, in which—

I claim:

The ornamental design for a lamp support substantially as shown.

MICHAEL W. SHILLINGER.
